CLAIM

The ornamental design for a swan planter-feeder, as shown and described.

DESCRIPTION

FIG. 1. Is a front perspective view of our swan planter feeder with the dotted line shown being for illustrative purposes only and to which no claim is made;

FIG. 2. Is a right side elevational view with the left side elevational view being a mirror image thereof with the dotted line shown being for illustrative purposes only and to which no claim is made;

FIG. 3. Is a front elevational view thereof with the dotted line shown being for illustrative purposes only and to which no claim is made;

FIG. 4. Is a rear elevational view thereof with the dotted line shown being for illustrative purposes only and to which no claim is made;

FIG. 5. Is a top plan view thereof with the dotted line shown being for illustrative purposes only and to which no claim is made; and,

FIG. 6. Is a bottom plan view thereof with the dotted line shown being for illustrative purposes only and to which no claim is made.
